UNITED STATES PATENT OFFICE.

OTTO E. FLOHR, OF TOLNA, NORTH DAKOTA.

LIFTING-JACK.

1,349,195.

Specification of Letters Patent. Patented Aug. 10, 1920.

Application filed May 24, 1919. Serial No. 299,542.

To all whom it may concern:

Be it known that I, OTTO E. FLOHR, a citizen of the United States, residing at Tolna, in the county of Nelson and State of North Dakota, have invented certain new and useful Improvements in Lifting-Jacks, of which the following is a specification.

This invention relates to lifting jacks, of the type known as lever lifting jacks.

10 The object of the invention is to provide a simple, strong jack of this character equipped with simple and efficient means for holding the lever after the lifting operation has been effected.

15 Another object of the invention is to provide a lifting jack in which the locking of the parts after adjustment will be entirely automatic.

20 With the foregoing and other objects in view, which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawings:—

30 Figure 1 represents a side elevation of a lifting jack constructed in accordance with this invention with the object supporting member shown raised in full lines and lowered in dotted lines.

35 Fig. 2 is a transverse section taken on the line 2—2 of Fig. 1, and

Fig. 3 is a detail sectional view through the supporting arm, the lifting bar on which it is mounted being shown broken off for 40 convenience in illustration.

In the embodiment illustrated, the jack constituting this invention comprises a suitable base 1 from which rises a standard 2 fixed to the base in any suitable manner. 45 The upper end of this standard 2 is bifurcated and is shown reinforced by a metal strap 3.

A lever 4 is fulcrumed in one end between the furcations of the standard 2 as shown 50 at 5 and this lever has an elbow 6 positioned at the rear of its fulcrum, the handle 4^a thereof being much longer than the end 4^b on the other side of its fulcrum.

55 A lifting bar 7 is pivoted at its upper end to the free end of the arm 4^b of lever 4. This

lifting bar 7 is guided at its lower end in an aperture 10 formed in the brace 9 which connects the standard 2 with the base 1. It will thus be seen that this member 9 performs the double function of a brace and a 60 guide.

A supporting arm 11 is adjustable vertically upon the lifting bar 7 and has a collar 12 encircling said bar, the inner diameter of the collar being slightly greater than the 65 diameter of the bar 7 as is shown clearly in Fig. 3, so that when the weight W. rests on and is supported by the arm 11, the diagonally opposite edges of the collar will bite into the bar and securely lock the arm in 70 adjusted position.

A lever locking member is shown in the form of a spring metal bar 13 bolted at one end to the standard 2 intermediately of its ends and positioned obliquely in relation to 75 the standard, the free end of said bar 13 being hook-shaped as shown at 14 and which is designed to engage lever 4 after it has been lowered for effecting the lifting operation as shown in Figs. 1 and 2, and thereby reliably 80 retain it in this position.

In the use of this invention, the supporting arm 11 is adjusted beneath the axle of a vehicle or other object to be raised and the lever 4 is then thrown down, causing the 85 lifting bar 7 to be elevated and the strain exerted by the weight of the object lifted on the arm 11, will cause the collar to bite at its diagonally opposite front and rear edges into the bar 7 as shown in Fig. 3 and 90 consequently will be held secured to the bar and will be moved upward, therewith on the lowering of the lever.

After the supporting arm 11 has been moved to the desired extent, the hook 14 of 95 bar 13 is engaged with the lever as shown in Figs. 1 and 2, and the parts thus held in this position, with the lifting arm 11 and the object mounted thereon in elevated position as shown in full lines in Fig. 1. 100

From the foregoing description, taken in connection with the accompanying drawings, the advantages of the construction and of the method of operation will be readily apparent to those skilled in the art to which 105 the invention appertains and while I have described the principle of operation of the invention together with the device which I now consider to be the best embodiment thereof, I desire to have it understood that 110

the device shown is merely illustrative and that such changes may be made as are within the scope of the claimed invention.

Having thus fully described my invention, 5 what I claim as new and desire to secure by Letters Patent, is:—

A lifting jack comprising a supporting base, a standard rising therefrom with its upper end bifurcated and having a metal 10 strap extending over and connecting the furcations thereof, a substantially elbow-shaped lever fulcrumed intermediately of its ends adjacent the bend thereof between said furcations under said strap, one end of said 15 lever being longer than the other, a lifting

bar pivoted at its upper end to the terminal of the short end of said lever, and an upwardly and outwardly inclined spring metal bar fixed at one end to said standard and projecting on the side thereof opposite to that carrying the lifting bar, said metal bar having a hook at its free end for engaging the long end of said lever when in lowered position. 20

In testimony whereof I affix my signature 25 in presence of two witnesses.

OTTO E. FLOHR.
